FIG. 4 is a left side view thereof;

FIG. 5 is a right side view thereof;

FIG. 6 is a top view thereof;

FIG. 7 is a bottom view thereof; and

FIG. 8 is a perspective view of a connector in a second embodiment.

FIG. 9 is a front view of FIG. 8.

FIG. 10 is a top view of FIG. 8.

FIG. 11 is a perspective view of a connector in a third embodiment.

FIG. 12 is a front view of FIG. 11.

FIG. 13 is a top view of FIG. 11.

FIG. 14 is a perspective view of a connector in a fourth embodiment.

FIG. 15 is a front view of FIG. 14.

FIG. 16 is a top view of FIG. 14.

FIG. 17 is a perspective view of a connector in a fifth embodiment.

FIG. 18 is a front view of FIG. 17.

FIG. 19 is a top view of FIG. 17.

FIG. 20 is a perspective view of a connector in a sixth embodiment.

FIG. 21 is a front view of FIG. 20.

FIG. 22 is a top view of FIG. 20.

(Continued)

FIG. 23 is a perspective view of a connector in a seventh embodiment.

FIG. 24 is a front view of FIG. 23.

FIG. 25 is a top view of FIG. 23.

FIG. 26 is a perspective view of a connector in an eighth embodiment.

FIG. 27 is a front view of FIG. 26; and,
